Inventor,
Emanuel A. Rich,
By J. W. Barker

Attorney.

UNITED STATES PATENT OFFICE.

EMANUEL A. RICH, OF NEW YORK, N. Y.

MOISTENING DEVICE FOR CIGAR-BOXES.

SPECIFICATION forming part of Letters Patent No. 512,121, dated January 2, 1894.

Application filed February 2, 1893. Serial No. 460,711. (No model.)

To all whom it may concern:

Be it known that I, EMANUEL ADOLPH RICH, a citizen of the United States, residing at New York, in the county and State of New York, 5 have invented certain new and useful Improvements in Cigar-Moistening Devices for Cigar-Boxes, of which the following is a full, clear, and exact specification.

My invention relates to cigar moistening devices, and more particularly to a moistener which is applicable to cigar boxes which have been packed with cigars and placed on the dealers' shelves for sale, or for use by the consumer.

It is well known that a great trouble experienced by cigar dealers and consumers in the use of cigars, is that when kept in a dry place, or from natural causes, the cigars become so dry as to be unfit for use; and the object of my invention is to provide a means within the boxes in which cigars are packed, whereby the cigars may be moistened and kept in a moist condition for any length of time.

Referring to the drawings, forming a part 25 of this specification, Figure 1 is a perspective view of a cigar box having my improved moistening device applied thereto. Fig. 2 is a side elevation of the moistening device removed. Fig. 3 is a vertical cross section of the same, 30 taken on line 1—1 of Fig. 2.

A represents a cigar box, and B a receiver for the moistener C. As will be seen by the drawings the receiver B is constructed of two 35 separate plates, said plates being connected together at the sides and bottom, and secured one to the other in such manner as to form a pocket. The top of said receiver B is open to permit the insertion or removal of the moistener C. The front plate a is perforated at 40 its upper portion for a purpose to be described hereinafter, and the back plate b is solid over its entire surface.

The moistening device C is formed of a strip of metal folded upon itself, and is adapted 45 to receive within the fold a suitable absorbent material, such as blotting paper, felt, &c. As seen in the drawings I prefer to use three thicknesses of blotting paper c for this purpose.

50 The moistening device C is provided with

perforations in its upper side portion for the purpose of enabling the absorbent material to receive and exhale moisture. The moistening device C when charged with moisture is adapted to be inserted within the receiver, 55 when moisture will be caused to enter the box through the perforations in both the moistening device and the receiver.

The device C is moistened by dipping it inverted in water, allowing it to remain in the water only a sufficient length of time for the outside sheets of blotting to become saturated. By this means the middle sheet of blotting will absorb any superfluous water. The lower portion of the device C is solid to 65 prevent the absorbent material contained in said portion from receiving moisture. The device C being inserted in the receiver, the moisture with which the upper portion of the absorbent material has been saturated will 70 gradually soak down toward the lower edge, and that portion of the absorbent material which is covered by the solid lower portion of the device C will absorb some of the superfluous moisture. Notwithstanding these provisions to prevent water from flowing into the box, it is possible that a few drops might escape from the device C. To prevent these drops from entering the box and damaging 75 the cigars, the lower portion (not perforated) 80 of the receiver B is formed in the shape of a trough which serves to collect any escaping water.

The moistening device C is provided with a lip or shoulder d by which it may be removed 85 from the receiver.

My invention as described does not necessitate any alteration in the construction of the ordinary cigar boxes, and in this form it is applicable for use where the boxes are sold 90 intact to the consumer, who can use the moistener after he has bought and opened the box.

Where it is desired to preserve the cigars in their boxes in a moist condition without opening said boxes or breaking the revenue 95 stamps, I provide an auxiliary lid D directly over the receiver B. This lid may be opened without violating the internal revenue laws, as the goods could not be removed through such opening, but would permit of the re- 100

moval and insertion of the moistening device with ease, thus preserving the goods in a proper condition for use.

Having now described my invention, I de-
clare that what I claim is—

The combination with a cigar box, of a receiv-
ing device B within said box, said receiv-
ing device formed of two plates secured to-
gether, closed at the sides and bottom, and
open at the top, one plate having perforations
along its upper portion; a removable mois-
tening device contained within said receiver
comprising a strip of metal folded upon it-
self, one of the flaps formed thereby being

provided with perforations; absorbent mate- 15
rial within the fold; a lip to facilitate the re-
moval of the moistening device from the re-
ceiver, and an auxiliary box lid D situate
over the mouth of the receiver, substantially
as and for the purposes herein shown and de- 20
scribed.

In testimony that I claim the foregoing I
have hereunto set my hand this 30th day of
January, 1893.

EMANUEL A. RICH.
